Patented Sept. 23, 1919.

FIG. 1.

FIG. 2.

William J. Thomson Inventor
By his Attorneys
Eugene, Booth, Jerny & Rooney

UNITED STATES PATENT OFFICE.

WILLIAM I. THOMSON, OF NEWARK, NEW JERSEY, ASSIGNOR TO SAFETY CAR HEATING & LIGHTING COMPANY, A CORPORATION OF NEW JERSEY.

SYSTEM OF DISTRIBUTION.

1,316,603.

Specification of Letters Patent. Patented Sept. 23, 1919.

Application filed December 14, 1916. Serial No. 136,928.

To all whom it may concern:

Be it known that I, WILLIAM I. THOMSON, a citizen of the United States, and a resident of Newark, in the county of Essex 5 and State of New Jersey, have invented an Improvement in Systems of Distribution, of which the following is a specification.

This invention relates to electrical systems of distribution and with regard to certain more specific features to regulating apparatus for lighting systems of cars and the like. One of the objects thereof is to provide a simple and dependable system of the above type which will be readily adaptable 15 to meet changes in conditions of use. Other objects are to provide a system of the above type of efficient and accurate action in which the manipulation of the parts is simple and does not require care or skill. Other objects 20 will be in part obvious and in part pointed out hereinafter.

The invention accordingly consists in the features of construction, combinations of elements and arrangement of parts which will 25 be exemplified in the structure hereinafter described and the scope of the application of which will be indicated in the following claims.

In the accompanying drawing in which 30 is shown one of various possible embodiments of this invention,

Figure 1 is a diagrammatic plan; and

Fig. 2 is a detail plan of a connecting device.

Similar reference characters refer to similar parts throughout the several views of the drawing.

Referring now to Fig. 1 of the drawing, there is shown at 1 a generator having a 40 shunt field winding 2 in which is serially connected a variable resistance element 3 preferably comprising a pile of carbon disks, the aggregate resistance of which varies with the pressure with which they are 45 compressed.

One of the leads 4 of this generator 1 passes through the current coil 5 of an ordinary automatic switch, thence through the spring-retracted contact 6 of that switch to 50 the main 7. Serially positioned in this main is a current regulating solenoid 8, and connected between this main and the main 9 and parallel one with another are the storage battery 10 and the lamps 11.

55 Bridged across the generator is a voltage

coil 12 which in conjunction with the series coil 5 controls the position of the automatic switch contact 6.

The pressure upon the resistance element 3 is brought about by a pair of bell crank 60 levers 13 and 14 each urged as by the springs 15 in a direction in which they press upon the carbon pile and tend to reduce its resistance. The lever 13 is pivotally connected with a core 16 in the solenoid 8 and as 65 it swings in response to the tendencies to variation in current, it correspondingly varies the field resistance at 3 to maintain the current output constant.

Pivotally connected with the lever 14 is a 70 core 17 co-acting with a voltage solenoid 18 bridged across the mains in series with a resistance element 19. This last solenoid upon attaining sufficient field strength will so relieve the pressure upon the carbon pile 75 as materially to reduce the generator voltage.

Serially connected in the branch leading from the battery 10 is an ampere hour meter 20 the actuating coil of which is indicated at 80 21. This instrument acts in the usual way to swing an arm 22, in this case a contact, in one direction as current passes into the battery, and in the opposite direction as current is drawn out. When this contact arm 22 engages the stationary contact 23 which should be with the battery in fully charged condition, the circuit is completed from a post 24 to a post 25. These posts are respectively 85 electrically connected with one end of the 90 resistance element 19 and with a point 26 intermediate the ends of this element. Thus with the battery fully charged, a low resistance shunt or substantially short circuit is completed about a considerable portion of 95 the resistance element 19, resulting in a largely increased flow of current through the solenoid 18. When this occurs, the latter solenoid is empowered to so reduce the pressure on the carbon pile 3 that charging 100 of the storage battery 10 will substantially cease.

If the type of battery be changed, as for example, a change from a lead battery to one of the Edison type, or the reverse, there 105 is often a change of voltage at which the battery is fully charged. For best action of the regulating apparatus, however, the ampere turns or magnetic effect of the solenoid 18 should be held substantially free from 110

change due to such substitution of batteries. I have accordingly provided means whereby, with an extremely simple adjustment, the apparatus is readily adaptable for change 5 from one to the other of these systems of batteries without affecting the action of the coil 18. At suitable points on the resistance element 19, conductors 27 are led to posts 28. These posts are adjacent the posts 24 and 25 10 and are of the construction indicated in detail in Fig. 2 of the drawing. In the post 28 there is slidably mounted a contact pin 29 provided with a short stop pin 30 to limit its outward movement. This pin with open 15 condition of the connection is held in place by the set screw 31. In the post 24 in alignment with this pin is a recess adapted to receive the same, as indicated by the dotted lines 32, and a set screw 33 adapted to lock 20 it in connecting or closed position. When a higher voltage battery is employed, as for example one of the Edison type, these pins are held in the retracted position in full 25 lines and the full effect of the resistance 19 is utilized. Under lower voltage charging conditions with a lower voltage of the charged battery, as for example when a battery of the lead type is employed, the pins are slid into contact-making position with 30 the posts 24 and 25. By this action a section of the resistance 19 is continuously short-circuited from the post 28 to the post 24 irrespective of the position of the ampere hour 35 meter contact. Furthermore the closing of the circuit at the ampere hour meter shunts the entire resistance up to the point 34, thus requiring lower voltage to give the desired effect to the voltage coil 18. It may here be noted that the term "voltage coil" is used 40 in a broad sense to denote any electrical magnetic device whose effect is responsive to voltage changes. It may also be noted that the expression "regulating means" is broadly used.

45 From the above description, it is believed that the operation and method of use of this apparatus will be clear, but it may be noted that whenever a low voltage battery is substituted for one of a higher voltage type, it 50 is necessary merely to release the set screws 31, slide the pins 29 into the opposite posts and lock them in position by the set screws 33. This action will result without adjustment in precisely the desired operation of the 55 regulating means. By a reverse of the battery operation, the system is prepared for the substitution of a higher voltage battery. It will also be seen that the apparatus requires no skilled operator and that the devices employed to effect the change are thor- 60oughly reliable in action. The arrangement of the contact post construction is preferably that indicated in Fig. 2 of the drawing; with the contact pin horizontal rather than vertical, as indicated in the diagrammatic view,

thus accidental movement being precluded even independently of the set screws.

It will thus be seen that there is provided apparatus in which the several objects of this invention are achieved.

As various possible embodiments might be made of the above invention and as various changes might be made in the embodiment above set forth, it is to be understood that all matter herein set forth or shown in the accompanying drawing is to be interpreted as illustrative and not in a limiting sense.

I claim as my invention:

1. In apparatus of the class described, in combination, a generator, regulating means for said generator comprising a voltage coil, a resistance element connected with said coil, manually controlled means adapted to vary the resistance of said element, a storage battery adapted to be charged by said generator, and an ampere hour meter through which current is led to said battery adapted automatically when the battery has reached a predetermined state of charge to vary said resistance.

2. In apparatus of the class described, in combination, a generator, a storage battery adapted to be charged thereby, regulating apparatus for said generator comprising a voltage coil, manually controlled means adapted to vary the strength of said voltage coil, and means adapted automatically to change the strength of said coil upon said battery being charged by said generator to a predetermined extent.

3. In apparatus of the class described, in combination, a generator, a storage battery adapted to be charged thereby, regulating means for said generator comprising a voltage coil, means adapted automatically to change the strength of said voltage coil upon said battery being substantially fully charged, and manually controlled means adapted to change the strength of said coil to substantially the same degree both before and after the actuation of said automatic means.

4. In apparatus of the class described, in combination, a generator, a storage battery adapted to be charged thereby, regulating means for said generator comprising a voltage coil, a resistance element in series with said voltage coil, means actuated upon said battery reaching a certain state of charge adapted automatically to shunt a portion of said resistance element, and manually controlled means adapted to short-circuit portions of both the shunted and unshunted parts of said resistance element.

5. In apparatus of the class described, in combination, a generator, a storage battery adapted to be charged thereby, regulating means for said generator comprising a voltage coil, a resistance element in series with

said voltage coil, means actuated upon said battery reaching a certain state of charge adapted automatically to shunt a portion of said resistance element, and manually controlled means adapted to short-circuit portions of both the shunted and unshunted parts of said resistance element, said automatic means comprising an ampere hour meter traversed by current flowing through

10 said battery.

6. In apparatus of the class described, in combination, a generator, a storage battery adapted to be charged thereby, a voltage coil, a resistance element in series with said

voltage coil, an ampere hour meter traversed by charging current, means controlled by said ampere hour meter adapted to shunt a portion of said resistance element, and a pair of manually controlled devices respectively adapted to short-circuit portions of the shunted and of the unshunted parts of said resistance element, said devices being adapted to be maintained in either open or closed position.

In testimony whereof, I have signed my name to this specification this 12th day of December, 1916.

WILLIAM I. THOMSON.
